ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

MOTOR CONTROL APPARATUS

Application filed December 3, 1929. Serial No. 411,283.

My invention relates to motor control apparatus, and particularly to apparatus for controlling the operating motor for a railway switch from a remote point.

5 One feature of my invention is the provision of means for interrupting the motor circuit if the current supplied to the motor becomes excessive, and for subsequently preventing the motor circuit from being restored 10 until the device which controls the motor controller is operated.

I will describe one form of apparatus embodying my invention, and will then point out the novel features thereof in claims.

15 The accompanying drawing is a diagrammatic view showing one form of motor control apparatus embodying my invention applied to the control of an electric motor for operating a railway switch.

20 Referring to the drawing, the reference character S designates a railway switch which is operated by a motor M through the medium of a suitable switch-operating mechanism A. This mechanism forms no 25 part of my present invention, and its structure is therefore not shown in the drawing. This mechanism, however, comprises a rotatable shaft 65 adapted to receive a crank 66 by means of which the switch at times may 30 be manually operated.

Associated with the shaft 65 is a circuit controller F comprising a normally closed contact 11-11^a which is opened when the crank 66 is placed on the shaft 65, and a normally open contact 12-12^a which is closed when the crank 66 is placed on the shaft 65.

35 The switch S operates a circuit controller E comprising a contact 10-10^a which is closed at all times except when the switch occupies its extreme reverse position, and a contact 9-9^a which is closed at all times except when the switch occupies its extreme normal position, in which latter position it is 40 illustrated in the drawing.

45 The motor M is controlled by a motor controller, designated in general by the reference character D, which motor controller, in turn, is controlled by the circuit controllers E and F, and by a polarized relay R. The polarized relay R will usually be controlled

from a point remote from the motor controller D, such for example, as a train dispatcher's office, and may be controlled in any suitable manner as by pole-changing contacts on a manually operable switch lever. 55

The motor controller D, in the form here shown, comprises a normal contactor C^a and a reverse contactor C^r. These contactors are exactly alike and each comprises an armature 3, pivoted at 4, and controlled by a winding 5. Each armature 3 is operatively connected with three contacts 6, 7 and 8. When winding 5 of either contactor C^r or C^a is de-energized, armature 3 of this contactor occupies the position in which it is illustrated 60 in the drawing, and the associated contacts 6, 7 and 8 are open. When the winding 5 of the contactor is energized, however, armature 3 of this contactor is swung to a position in which the associated contacts 6, 7 and 8 65 become closed.

70 The armatures 3 of the contactors C^a and C^r are controlled by an interlocking rod 13 in such manner that the armature 3 of one contactor cannot be moved to the position in 75 which its associated contacts are closed unless the armature 3 of the other contactor occupies the position in which its associated contacts are open. The interlocking rod 13 is mounted to slide in suitable holes formed 80 in two fixed abutments 14, and is arranged to operate a circuit controller G. The circuit controller G, in the form here shown, comprises a contact 25-25^a which becomes closed when armature 3 of contactor C^a is moved to

85 the position where its associated contacts become closed, and which subsequently remains closed until just after armature 3 of contactor C^r has been moved to the position where its associated contacts become closed. The circuit controller G also comprises a contact 46-46^a which becomes closed when armature 3 of contactor C^r is moved to the position where its associated contacts become closed. 90 The motor controller D also comprises two thermal relays T^a and T^r, each comprising 95

100

a thermo-sensitive device and a heating element 18 for heating the device. As here shown, each thermo-sensitive device is a bimetallic strip 17 arranged in such manner that the free end of the strip will deflect upwardly when the associated heating element 18 is supplied with current, the magnitude of which exceeds the normal operating current for motor M. Each bimetallic strip 17 operates a contact 17-17^a which is normally closed, but which becomes opened when the associated bimetallic strip 17 is deflected.

As shown in the drawing, switch S occupies its normal position, so that contact 9-9^a of circuit controller E is open, and contact 10-10^a of circuit controller E is closed. Crank 66 is removed from the shaft 65, and contact 11-11^a of circuit controller F is therefore closed, while contact 12-12^a of circuit controller F is open. Motor M is de-energized. Contactors C^r and Cⁿ are both de-energized, and the contacts 6, 7 and 8 of these contactors are all open but contact 25-25^a of circuit controller G is closed. Thermal relays Tⁿ and T^r are both de-energized, and contact 17-17^a of each of these contactors is therefore closed. Polarized relay R is energized in its normal direction so that its front contact 21 and its normal contacts 23-23^a and 61-61^a are closed. I will now assume that with the parts in the positions just described the train despatcher wishes to reverse switch S. To do this, he reverses relay R so that relay R opens its normal contacts 23-23^a and 61-61^a, and closes its reverse contacts 23-23^b and 61-61^b. Current is then supplied to the winding 5 of contactor C^r from the terminals B and X of a suitable source of current not shown in the drawing over a pick-up circuit which passes from terminal B, through wire 20, front contact 21 of relay R, wire 22, reverse contact 23-23^b of relay R, wire 24, contact 25-25^a of circuit controller G, wires 26 and 27, winding 5 of contactor C^r, wire 28, contact 17-17^a of thermal relay T^r, and wire 29 to terminal X. As a result, winding 5 of contactor C^r becomes energized, so that armature 3 of this contactor is moved to the position in which its associated contacts 6, 7 and 8 become closed. When armature 3 is moved to this position, contact 25-25^a of circuit controller G is opened, thus interrupting the pick-up circuit just traced for winding 5 of contactor C^r, but since contact 6 of circuit controller C^r is then closed, winding 5 is maintained in its energized condition by virtue of a stick circuit which passes from terminal B, through wire 20, front contact 21 of relay R, wire 22, reverse contact 23-23^b of relay R, wires 24 and 40, contact 10-10^a of circuit controller E, wire 41, contact 6 of circuit controller C^r, wires 42, 43 and 27, winding 5 of contactor C^r, wire 28, contact 17-17^a of thermal relay T^r, and wire 29 to

terminal X. When contacts 7 and 8 of contactor C^r become closed, a circuit for motor M is completed, and current flows from terminal B, through wire 30, contact 8 of circuit controller C^r, wires 31 and 32, armature 1 of motor M, wires 33 and 34, contact 7 of contactor C^r, wire 35, heating element 18 of thermal relay T^r, wires 36 and 37, field winding 2 of motor M, wire 38, contact 11-11^a of circuit controller F, and wire 39 to terminal X. Motor M therefore operates to move switch S from its normal to its reverse position. When the switch reaches its full reverse position, contact 10-10^a of circuit controller E opens, thereby interrupting the stick circuit previously traced for winding 5 of contactor C^r, so that contactor C^r becomes de-energized and opens its contacts 6, 7 and 8. When contacts 7 and 8 of contactor C^r are opened, the circuit just traced for motor M is interrupted and the motor stops. All parts are then de-energized.

If, after the switch has reached its full reverse position, the train despatcher wishes to restore the switch to its normal position, he restores relay R to its normal position in which it is illustrated in the drawing. Since contact 46-46^a of circuit controller G is now closed, a pick-up circuit for winding 5 of contactor Cⁿ is completed from terminal B, through wire 20, front contact 21 of relay R, wire 22, normal contact 23-23^a of relay R, wires 44 and 45, contact 46-46^a of circuit controller G, wires 47 and 48, winding 5 of contactor Cⁿ, wire 49, contact 17-17^a of relay Tⁿ, and wire 50 to the other terminal X. Winding 5 of contactor Cⁿ therefore becomes energized so that armature 3 of this contactor is moved to the position in which its associated contacts 6, 7 and 8 are closed. When armature 3 is moved to this position, contact 46-46^a of circuit controller G opens and interrupts the pick-up circuit just traced for winding 5 of contactor Cⁿ, but contact 6 of circuit controller Cⁿ is then closed, and since contact 9-9^a of circuit controller E is closed, winding 5 is maintained in its energized condition by virtue of a stick circuit which passes from terminal B of the source, through wire 20, front contact 21 of relay R, wire 22, normal contact 23-23^a of relay R, wires 44 and 51, contact 9-9^a of circuit controller E, wire 52, contact 6 of contactor Cⁿ, wires 53 and 48, winding 5 of contactor Cⁿ, wire 49, contact 17-17^a of thermal relay Tⁿ, and wire 50 to terminal X. When contacts 7 and 8 of contactor Cⁿ becomes closed a circuit for motor M is completed which passes from terminal B, through wire 54, contact 7 of circuit controller Cⁿ, wires 55 and 33, armature 1 of motor M, wires 32 and 56, contact 8 of contactor Cⁿ, wire 57, heating element 18 of thermal relay Tⁿ, wires 58 and 37, field winding 2 of motor M, wire 38, contact 11-11^a of circuit controller F, and wire 39 to ter-

5 minal X. Motor M then restores switch A to its normal position. When the switch reaches its full normal position, contact 9-9^a of circuit controller E opens and de-energizes contactor Cⁿ. When contactor Cⁿ becomes de-energized, the contactor opens its contacts and interrupts the circuit just traced for motor M, so that the motor stops, and the parts are then restored to the position in 10 which they are illustrated in the drawing.

If, for any reason the motor current rises above the normal value while switch S is being moved from one extreme position to the other extreme position, the motor will be de-energized automatically, so that damage to the motor will be prevented. For example, I will assume that the motor current rises above the normal value when switch S is being moved from its normal to its reverse 15 position due, for example, to the movement of the switch being arrested by some obstruction before the switch reaches its full reverse position. As pointed out hereinbefore, when switch S is being moved from its normal to its reverse position, motor M is energized over a circuit which includes contacts 7 and 8 of contactor C^r and heating element 18 of thermal relay T^r. It will be apparent, therefore, that when the motor current rises 20 above the normal value under the above conditions, bimetallic strip 17 of thermal relay T^r becomes heated, and the end of the strip 17 deflects upwardly, thereby opening contact 17-17^a of this relay, and thus interrupting the stick circuit for contactor C^r. Contactor C^r therefore becomes de-energized and thus de-energizes motor M.

After motor M has been de-energized in this manner, motor M can not again be energized in the direction to move switch S towards its reverse position until thermal relay T^r has cooled sufficiently to close its contact 17-17^a and contact 25-25^a of circuit controller G has been closed, because, when either of these contacts are open, the pick-up circuit for winding 5 of contactor C^r is interrupted. In order to close contact 25-25^a of circuit controller G it is necessary to energize contactor Cⁿ, which can only be done by 45 reversing relay R to close its normal contact 23-23^a.

In similar manner, if the motor current rises above its normal value when switch S is being moved from its reverse to its normal 50 position, strip 17 of thermal relay Tⁿ deflects upwardly, and de-energizes contactor Cⁿ, thereby de-energizing motor M. Motor M can not then again be energized in the direction to move switch S towards its normal position until strip 17 of thermal relay Tⁿ cools and closes its contact 17-17^a, and until relay R is reversed to energize contactor C^r, and thus close contact 46-46^a of circuit controller G. For, when either contact 17-17^a of thermal relay Tⁿ or contact 46-46^a of circuit con-

troller G is open, the pick-up circuit for the normal contactor Cⁿ is interrupted so that contactor Cⁿ can not be energized.

It should be pointed out that if crank 66 is placed on shaft 65 in order to operate switch S manually, both circuits for motor M are then opened at contact 11-11^a of circuit controller F, and motor M can not, therefore, be energized under these conditions.

It should also be pointed out that if switch S is operated manually by means of crank 66 from the extreme position corresponding to the position which relay R occupies to an intermediate position, or to its other extreme position, then, as soon as crank 66 is removed from the shaft 65, the switch will be restored automatically to its proper position. For example, I will assume that switch S is operated manually from its normal position by means of crank 66 to either an intermediate position, or to its reverse position when relay R occupies its normal position. Under these conditions, as long as crank 66 is on shaft 65 both circuits for motor M are open at contact 11-11^a of circuit controller F, and an auxiliary pick-up circuit for winding 5 of contactor Cⁿ is closed at contact 12-12^a of circuit controller F, this auxiliary pick-up circuit passing from terminal B through contact 12-12^a of circuit controller F, wire 60, 80 normal contact 61-61^a of relay R, wires 63, 53 and 48, winding 5 of contactor Cⁿ, wire 49, contact 17-17^a of thermal relay Tⁿ and wire 50 to terminal X. Contactor Cⁿ therefore becomes energized and closes its contacts 6, 7 85 and 8. If crank 66 is then removed from shaft 65, the opening of contact 12-12^a of circuit controller F will interrupt the auxiliary pick-up circuit just traced for winding 5 of contactor Cⁿ, but since contact 6 of this contactor is now closed, the stick circuit previously traced for winding 5 is closed, and contactor Cⁿ will therefore remain energized. As a result, when contact 11-11^a of circuit controller F closes, motor M becomes energized and restores switch S to its normal position. When switch S reaches its normal position, contact 9-9^a of circuit controller E opens, thereby de-energizing contactor Cⁿ and thus de-energizing motor M. The parts are then restored to the positions in which they are illustrated in the drawing.

In similar manner, if switch S is operated manually from its reverse position to its normal position by means of crank 66 when relay R occupies its reverse position, then when crank 66 is removed from the shaft 65, the switch will be automatically restored to its reverse position. For, under these conditions, as long as crank 66 is on shaft 65, both circuits for motor M are interrupted at contact 11-11^a of circuit controller F, and an auxiliary pick-up circuit for winding 5 of contactor C^r is closed from terminal B, through wire 59, contact 12-12^a of circuit 100 105 110 115 120 125 130

controller F, wire 60, reverse contact 61—61^b of polarized relay R, wires 62, 43 and 27, winding 5 of contactor C^r, wire 28, contact 17—17^a of thermal relay T^r, and wire 29 to terminal X. Contactor C^r therefore picks up and is subsequently held up over its stick circuit. As a result, when crank 66 is removed from shaft 65 motor M becomes energized and restores switch S to its reverse position. When switch S reaches its full reverse position the stick circuit for winding 5 of contactor C^r is interrupted at contact 10—10^a of circuit controller E, and contactor C^r therefore becomes de-energized and de-energizes motor M. All parts are then de-energized.

While I have illustrated motor control apparatus embodying my invention as applied to the control of a motor for operating a railway switch, it will be readily understood that apparatus embodying my invention is not limited to this use, but may be applied to the control of any reversible motor for operating any movable device.

Although I have herein shown and described only one form of motor control apparatus embodying my invention, it is understood that various changes and modifications may be made therein within the scope of the appended claims without departing from the spirit and scope of my invention.

Having thus described my invention, what I claim is:

1. In combination, a movable device, an electric motor for operating said device, a first circuit controller operated by said device, two contactors, a second circuit controller operated by both said contactors, means including said circuit controllers for selectively energizing said contactors, and means controlled by said contactors for energizing said motor.

2. In combination, a railway traffic governing device having two positions, a manually controlled device capable of assuming different conditions, means for operating said railway traffic governing device to one position or the other in accordance with the condition of said manually controlled device, other means for at times manually operating said railway traffic governing device, and means effective after said railway traffic governing device has been manually operated for automatically restoring said railway traffic governing device to the position corresponding to the condition of said manually controlled device.

3. In combination, a railway switch having normal and reverse positions, a manually controlled polarized relay, means for operating said switch to its normal or reverse position according as said polarized relay is energized in one direction or the other, means for at times manually operating said switch, and means effective after said switch has

been manually operated for automatically restoring said switch to the position corresponding to the condition of said polarized relay.

4. In combination, a railway switch having normal and reverse positions, a manually controlled polarized relay, means for operating said switch to its normal or its reverse position according as said polarized relay is energized in one direction or the other, means for at times manually operating said switch, a contact which is operated when said switch is manually operated, and means controlled in part by said contact for automatically restoring said switch to the position corresponding to the condition of said polarized relay after said switch has been manually operated.

5. In combination, a railway switch, a manually controlled relay capable of assuming different conditions, a normally closed contact, a normally open contact, means including said normally closed contact for operating said switch to its normal or its reverse position in accordance with the condition of said relay, means for at times manually operating said switch, means for opening said normally closed contact and for closing said normally open contact when said switch is manually operated, and means controlled by said normally open contact for automatically restoring said switch to the position corresponding to the condition of said relay after said switch has been manually operated.

6. In combination, a movable device, mechanism including an electric motor for operating said device, a first and a second winding, means effective when said first winding is energized for supplying said motor with current to operate said motor in one direction, a first contact controlled by both said windings in such manner that said first contact becomes closed when said second winding is energized and subsequently remains closed until just after said first winding is energized, a normally closed contact arranged to be opened if the current supplied to said motor when said first winding is energized exceeds a predetermined value, means including said normally closed contact and said first contact for at times energizing said first winding, means for subsequently maintaining said first winding in its energized condition, and means for at other times energizing said second winding.

7. In combination, a movable device, mechanism including an electric motor for operating said device, a first and a second winding, means effective when said first winding is energized for supplying said motor with current to operate said motor in one direction, a first contact controlled by said first winding and arranged to become closed when said first winding is energized, a second contact controlled by both said windings in

such manner that said second contact becomes closed when said second winding is energized and subsequently remains closed until after said first contact becomes closed due to energization of said first winding, a normally closed contact arranged to be opened if the current supplied to said motor when said first winding is energized exceeds a predetermined value, means including said normally closed contact and said second contact for at times energizing said first winding, means including said first contact for subsequently maintaining said first winding in its energized condition, and means for at other

15 times energizing said second winding.

8. In combination, a movable device, mechanism including an electric motor for operating said device, a first and a second winding, means effective when said first
20 winding is energized for supplying said motor with current to operate said motor in one direction, a first contact controlled by said first winding and arranged to become closed when said first winding is energized,
25 a second contact controlled by both said windings in such manner that said second contact becomes closed when said second winding is energized and subsequently remains closed until after said first contact
30 becomes closed due to energization of said first winding, a normally closed contact arranged to be opened if the current supplied to said motor when said first winding is energized exceeds a predetermined value,
35 manually controlled means including said normally closed contact and said second contact for at times energizing said first winding, manually controlled means including said first contact for subsequently maintaining
40 said first winding in its energized condition, and manually controlled means for at other times energizing said second winding.

9. In combination, a device capable of assuming a first or a second position, mechanism including an electric motor for operating said device, a first and a second winding, means effective when said first winding is energized for supplying said motor with current to move said device from said first position to said second position, a first contact controlled by said first winding and arranged to become closed when said first winding is energized, a second contact controlled by both said windings in such manner that said second contact becomes closed when said second winding is energized and remains closed until just after said first contact becomes closed due to energization of said first winding, a third contact controlled by said device and arranged to be closed at all times except when said device occupies its second position, a normally closed contact arranged to be opened if the current supplied to said motor exceeds a

predetermined value when said first winding is energized, means including said second contact and said normally closed contact for at times energizing said first winding, means including said first contact, said 70 normally closed contact, and said third contact for subsequently maintaining said first winding in its energized condition, and manually controlled means for at times energizing said second winding. 75

10. In combination, a device capable of assuming a first or a second position, mechanism including an electric motor for operating said device, said mechanism being provided with a rotatable shaft adapted to receive a crank for at times manually operating said device, a first and a second winding, means effective when said first winding is energized for supplying said motor with current to move said device from said first position to said second position, a first contact controlled by both said windings in such manner that said first contact becomes closed when said second winding is energized and subsequently remains closed until just after said first winding is energized, a normally closed contact arranged to be opened if the current supplied to said motor when said first winding is energized exceeds a predetermined value, means including said normally closed contact and said first contact for at times energizing said first winding, a normally open contact which becomes closed when said crank is placed on said shaft, means including said normally open contact for at other times energizing said first winding, means for subsequently maintaining said first winding in its energized condition, and means for at times energizing said second winding.

11. In combination, a device capable of assuming a first or a second position, mechanism including an electric motor for operating said device, said mechanism being provided with a rotatable shaft adapted to receive a crank for at times manually operating said device, a first and a second winding, a circuit controller comprising a normally open contact which becomes closed when said crank is placed on said shaft and a first normally closed contact which becomes opened when said crank is placed on said shaft, means controlled by said first winding and including said first normally closed contact for energizing said motor to move said device from said first position to said second position, a third contact controlled by said first winding and arranged to become closed when said first winding is energized, a fourth contact controlled by both said windings in such manner that said fourth contact becomes closed when said second winding becomes energized and remains closed until after said third contact becomes closed due to energization of said first winding, a fifth 110
115
120
125
130

contact controlled by said device and arranged to be closed at all times except when said device occupies its second position, a second normally closed contact arranged to be opened if the current supplied to said motor exceeds a predetermined value when said first winding is energized, means including said fourth contact and said second normally closed contact for at times energizing said first winding, means including said normally open contact and second normally closed contact for at other times energizing said first winding; means including said third contact, said second normally closed contact and said fifth contact for maintaining said first winding in its energized condition after said first winding becomes energized; and manually controlled means for at times energizing said second winding.

12. In combination, a device capable of assuming a first or a second position, mechanism including an electric motor for operating said device, a first and a second winding means effective when said first winding is energized for supplying said motor with current to move said device from said first position to said second position, means effective when said second winding is energized for supplying said motor with current to move said device from said second position to said first position, a first contact controlled by said first winding and arranged to become closed when said first winding is energized, a second contact controlled by said second winding and arranged to become closed when said second winding is energized, a third contact controlled by both said windings in such manner that said third contact becomes closed when said second winding is energized and subsequently remains closed until just after said first contact becomes closed due to energization of said first winding, a fourth contact controlled by both said windings in such manner that said fourth contact becomes closed when said first winding is energized and subsequently remains closed until just after said second contact becomes closed due to energization of said second winding, a fifth contact controlled by said device and arranged to be closed at all times except when said device occupies its second position, a sixth contact controlled by said device and arranged to be closed at all times except when said device occupies its first position, a first normally closed contact arranged to be opened if the current supplied to said motor exceeds a predetermined value when said first winding is energized, a second normally closed contact arranged to be opened if the current supplied to said motor exceeds a predetermined value when said second winding is energized, means including said third contact and said first normally closed contact for energizing said first winding; means including said first normally

closed contact, said first contact, and said fifth contact for subsequently maintaining said first winding in its energized condition; means including said fourth contact and said second normally closed contact for energizing said second winding; and means including said second normally closed contact, said second contact, and said sixth contact for subsequently maintaining said second winding in its energized condition.

13. In combination, a railway switch having normal and reverse positions, operating mechanism including an electric motor for operating said switch, said operating mechanism being provided with a rotatable shaft adapted to receive a crank for at times manually operating said switch, a first circuit controller associated with said mechanism and comprising a first contact which is normally closed but which becomes opened when said crank is placed on said shaft and a second contact which is normally open but which becomes closed when said crank is placed on said shaft, a first contactor comprising a first winding, a first pivoted armature controlled by said winding, and contacts controlled by said first armature; a second contactor comprising a second winding, a second pivoted armature, and contacts controlled by said second armature; a first thermal relay comprising a bimetallic strip which deflects when heated, a first heating element for heating said first strip, and a first normally closed contact which becomes opened when said first strip is deflected; a second thermal relay comprising a second bimetallic strip which deflects when heated, a second heating element for heating said second strip, and a second normally closed contact which becomes opened when said second strip is deflected; a polarized relay having normal and reverse contacts; a second circuit controller controlled by said first and second armatures and comprising a third contact which becomes closed when said first armature is moved to the position where its associated contacts are closed and which subsequently remain closed until just after said second armature is moved to the position where its associated contacts are closed, and a fourth contact which becomes closed when said second armature is moved to the position where its associated contacts are closed and which subsequently remains closed until just after said first armature is moved to the position where its associated contacts are closed; a third circuit controller operated by said switch and comprising a fifth contact which is closed at all times except when said switch occupies its extreme reverse position, and a sixth contact which is closed at all times except when said switch occupies its extreme normal position; a pick-up circuit for said first winding including a reverse contact of said polarized relay, said fourth contact, and

- said first normally closed contact of said first thermal relay, a stick circuit for said first winding including said reverse contact of said polarized relay, a contact of said first 5 contactor, said fifth contact, and said first normally closed contact of said first thermal relay; an auxiliary pick-up circuit for said first winding including a reverse contact of said polarized relay, said second contact of 10 said first circuit controller, and said first normally closed contact of said first thermal relay; a pick-up circuit for said second winding including a normal contact of said polarized relay, said third contact, and said 15 normally closed contact of said second thermal relay; a stick circuit for said second winding including said normal contact of said polarized relay, a contact of said second contactor, said sixth contact, and said second 20 normally closed contact of said second thermal relay; an auxiliary pick-up circuit for said second winding including said contact, a normal contact of said polarized relay, and said normally closed contact of said second 25 thermal relay; a first circuit for said motor including contacts of said first contactor, said first heating element, and said first contact; and a second circuit for said motor including contacts of said second contactor, said second 30 heating element, and said first contact.
14. In combination, a device capable of assuming a first or a second position, mechanism including an electric motor for operating said device, said mechanism being provided with a rotatable shaft adapted to receive a crank for at times manually operating said device, a first and a second winding, a first normally closed contact which becomes opened when said crank is placed on said 35 shaft, means controlled by said first winding and including said first normally closed contact for energizing said motor to move said device from said first position to said second position, a second contact controlled by both 40 said windings in such manner that said second contact becomes closed when said second winding is energized and subsequently remains closed until just after said first winding is energized, a second normally closed 45 contact arranged to be opened if the current supplied to said motor when said first winding is energized exceeds a predetermined value, means including said second normally closed contact and said second contact for at 50 times energizing said first winding, means for subsequently maintaining said first winding in its energized condition, and means for at other times energizing said second winding.
15. In combination, a railway traffic governing device having two positions, a manually controlled device capable of assuming different conditions, operating means for moving said railway traffic governing device to one position or the other in accordance 55 with the condition of said manually controlled device, other means for at times manually operating said railway traffic governing device, means for rendering said operating means ineffective during manual operation, and other means effective after said railway traffic governing device has been manually operated for automatically restoring said railway traffic governing device to the position corresponding to the condition of 70 said manually controlled device. 75
16. In combination, a railway traffic governing device having two positions, a manually controlled device capable of assuming different conditions, means for operating said railway traffic governing device to one position or the other in accordance with the condition of said manually controlled device, other means for at times manually operating said railway traffic governing device, a contact which is operated when said traffic governing device is manually operated, and means controlled in part of said contact effective after said railway traffic governing device has been manually operated for automatically restoring said railway traffic governing device to the position corresponding to the condition of said manually controlled device. 80
17. In combination, an electric motor, a first and a second winding, means effective when said first winding is energized for supplying said motor with current to operate said motor in one direction, a contact controlled by both said windings in such manner that said contact becomes closed when said second winding is energized and subsequently remains closed until just after said first winding is energized, means including said contact for at times energizing said first winding, means for subsequently maintaining said first winding in its energized condition, and means for at other times energizing said second winding. 90
18. In combination, an electric motor, a first and a second winding, means effective when said first winding is energized for supplying said motor with current to operate said motor in one direction, means effective when said second winding is energized for supplying said motor with current to operate said motor in the other direction, a first contact controlled by both said windings in such manner that said contact becomes closed when said second winding is energized and subsequently remains closed until just after said first winding is energized, a second contact controlled by both said windings in such manner that said contact becomes closed when said first winding is energized and subsequently remains closed until just after said second winding is energized, means including said first contact for energizing said first winding, means for subsequently maintaining said first winding in its energized condition. 100
19. In combination, a device capable of assuming a first or a second position, mechanism including an electric motor for operating said device, said mechanism being provided with a rotatable shaft adapted to receive a crank for at times manually operating said device, a first and a second winding, a first normally closed contact which becomes opened when said crank is placed on said shaft, means controlled by said first winding and including said first normally closed contact for energizing said motor to move said device from said first position to said second position, a second contact controlled by both said windings in such manner that said second contact becomes closed when said second winding is energized and subsequently remains closed until just after said first winding is energized, a second normally closed contact arranged to be opened if the current supplied to said motor when said first winding is energized exceeds a predetermined value, means including said second normally closed contact and said second contact for at times energizing said first winding, means for subsequently maintaining said first winding in its energized condition, and means for at other times energizing said second winding. 110
20. In combination, a device capable of assuming a first or a second position, mechanism including an electric motor for operating said device, said mechanism being provided with a rotatable shaft adapted to receive a crank for at times manually operating said device, a first and a second winding, a first normally closed contact which becomes opened when said crank is placed on said shaft, means controlled by said first winding and including said first normally closed contact for energizing said motor to move said device from said first position to said second position, a second contact controlled by both said windings in such manner that said second contact becomes closed when said second winding is energized and subsequently remains closed until just after said first winding is energized, a second normally closed contact arranged to be opened if the current supplied to said motor when said first winding is energized exceeds a predetermined value, means including said second normally closed contact and said second contact for at times energizing said first winding, means for subsequently maintaining said first winding in its energized condition, and means for at other times energizing said second winding. 115
21. In combination, a device capable of assuming a first or a second position, mechanism including an electric motor for operating said device, said mechanism being provided with a rotatable shaft adapted to receive a crank for at times manually operating said device, a first and a second winding, a first normally closed contact which becomes opened when said crank is placed on said shaft, means controlled by said first winding and including said first normally closed contact for energizing said motor to move said device from said first position to said second position, a second contact controlled by both said windings in such manner that said second contact becomes closed when said second winding is energized and subsequently remains closed until just after said first winding is energized, a second normally closed contact arranged to be opened if the current supplied to said motor when said first winding is energized exceeds a predetermined value, means including said second normally closed contact and said second contact for at times energizing said first winding, means for subsequently maintaining said first winding in its energized condition, and means for at other times energizing said second winding. 120
22. In combination, a device capable of assuming a first or a second position, mechanism including an electric motor for operating said device, said mechanism being provided with a rotatable shaft adapted to receive a crank for at times manually operating said device, a first and a second winding, a first normally closed contact which becomes opened when said crank is placed on said shaft, means controlled by said first winding and including said first normally closed contact for energizing said motor to move said device from said first position to said second position, a second contact controlled by both said windings in such manner that said second contact becomes closed when said second winding is energized and subsequently remains closed until just after said first winding is energized, a second normally closed contact arranged to be opened if the current supplied to said motor when said first winding is energized exceeds a predetermined value, means including said second normally closed contact and said second contact for at times energizing said first winding, means for subsequently maintaining said first winding in its energized condition, and means for at other times energizing said second winding. 125
23. In combination, a device capable of assuming a first or a second position, mechanism including an electric motor for operating said device, said mechanism being provided with a rotatable shaft adapted to receive a crank for at times manually operating said device, a first and a second winding, a first normally closed contact which becomes opened when said crank is placed on said shaft, means controlled by said first winding and including said first normally closed contact for energizing said motor to move said device from said first position to said second position, a second contact controlled by both said windings in such manner that said second contact becomes closed when said second winding is energized and subsequently remains closed until just after said first winding is energized, a second normally closed contact arranged to be opened if the current supplied to said motor when said first winding is energized exceeds a predetermined value, means including said second normally closed contact and said second contact for at times energizing said first winding, means for subsequently maintaining said first winding in its energized condition, and means for at other times energizing said second winding. 130

tion, means including said second contact for at other times energizing said second winding, and means for subsequently maintaining said second winding in its energized condition.

19. In combination, an electric motor, a first and a second winding, an operating circuit for said motor controlled by said first winding, a contact controlled by both said windings in such manner that said contact becomes closed when said second winding is energized and subsequently remains closed until just after said first winding is energized, means responsive to the magnitude of the current supplied to said motor when said first winding is energized for modifying the control of said operating circuit by said first winding, means including said contact for energizing said first winding, means for subsequently maintaining said first winding in its energized condition, and means for at other times energizing said second winding.

20. In combination, a device capable of assuming a first or a second position, mechanism including an electric motor for operating said device from said first to said second position, means for at times manually operating said device, a first and a second winding, an operating circuit for said motor controlled by said first winding, a first contact controlled by both said windings in such manner that said first contact becomes closed when said second winding is energized and subsequently remains closed until just after said first winding is energized, means responsive to the magnitude of the current supplied to said motor when said first winding is energized for modifying the control of said operating circuit by said first winding, means including said first contact for at times energizing said first winding, a second contact operated when said device is manually operated, means including said second contact for at other times energizing said first winding, means for subsequently maintaining said first winding in its energized condition, and means for at times energizing said second winding.

21. In combination, a device capable of assuming a first or a second position, mechanism including an electric motor for operating said device, a first and a second winding, a normal operating circuit for said motor controlled by said first winding for moving said device from said first to said second position, a reverse operating circuit for said motor controlled by said second winding for moving said device from said second to said first position, a first contact controlled by said first winding and arranged to become closed when said first winding is energized, a second contact controlled by said second winding and arranged to become closed when said second winding is energized, a third contact controlled by both said windings in such manner that said third contact becomes closed when

said second winding is energized and subsequently remains closed until just after said first contact becomes closed due to energization of said first winding, a fourth contact controlled by both said windings in such manner that said fourth contact becomes closed when said first winding is energized and subsequently remains closed until just after said second contact becomes closed due to the energization of said second winding, a fifth contact controlled by said device and arranged to be closed at all times except when said device occupies its second position, a sixth contact controlled by said device and arranged to be closed at all times except when said device occupies its first position, means responsive to the magnitude of the current supplied to said motor when said first winding is energized for modifying the control of said normal operating circuit by said first winding, means responsive to the magnitude of the current supplied to said motor when said second winding is energized for modifying the control of said reverse operating circuit by said second winding, means including said third contact for energizing said first winding, means including said first contact and said fifth contact for subsequently maintaining said first winding in its energized condition, means including said fourth contact for energizing said second winding, and means including said second contact and said sixth contact for subsequently maintaining said second winding in its energized condition.

In testimony whereof I affix my signature.

ROBERT M. GILSON.

DISCLAIMER

1,833,521.—*Robert M. Gilson*, Pittsburgh, Pa. MOTOR CONTROL APPARATUS.
Patent dated November 24, 1931. Disclaimer filed June 22, 1933, by the
assignee, *The Union Switch & Signal Company*.

Hereby enters the following disclaimer, to wit:

Your petitioner hereby disclaims the subject matter of claims 2, 3, 4, 5, 15, and 16.
[*Official Gazette July 18, 1933.*]
